Primary Examiner — Susan Moon Lee(74) *Attorney, Agent, or Firm* — Hanley, Flight & Zimmerman, LLC.(57) **CLAIM**

We claim the ornamental design for a UICC apparatus, as shown and described.

DESCRIPTION

FIG. 1 is a plan view of a UICC apparatus;

FIG. 2 is a front view of the UICC apparatus of FIG. 1;

FIG. 3 is a right side view of the UICC apparatus of FIG. 1;

FIG. 4 is a left side view of the UICC apparatus of FIG. 1; and,

FIG. 5 is a rear view of the UICC apparatus of FIG. 1.

Broken lines and portions contained within broken lines are not claimed.

1 Claim, 1 Drawing Sheet(56)
